UNITED STATES PATENT OFFICE.

HALVER R. STRAIGHT, OF ADEL, IOWA.

BUILDING BRICK.

Application filed March 8, 1926. Serial No. 93,241.

The object of my invention is to provide a building brick or the like so constructed that the drying and burning and cooling of the brick in its process of manufacture may be 5 more rapidly accomplished without setting up excessive shrinkage strains, and at the same time provides means whereby the shearing strength between the brick and the mortar joints, when they are supported in a wall 10 construction, will be greatly increased, and the tendency of the brick to float in green mortar, while being laid, is decreased.

My invention consists in the construction, arrangement and combination of the various 15 parts of the device, whereby the objects contemplated are attained, as hereinafter more fully set forth, pointed out in my claims, and illustrated in the accompanying drawings, in which:

20 Figure 1 is a plan view of my improved brick.

Figure 2 is a side elevation of same, a portion of which is shown in section.

25 Figure 3 is an end elevation of same, a portion of which is in section.

Figure 4 is a diagrammatical view illustrating the manner in which the drying takes place with my improved construction.

30 Figure 5 is a diagrammatical view showing the manner in which the drying takes place in the ordinary construction.

Figure 6 is a segmental plan view of a modified form of my improved brick.

I have found that if an undried brick of 35 rectangular cross section is placed in a drier and subjected to rapid drying, the brick will dry more rapidly near the outer surfaces than at its center, and set up shrinkage strains to such an extent that warping or 40 cracking will take place.

I have also found that when the brick is thus rapidly dried, the moist area or undried center gradually assumes the shape of an ellipse, as viewed in cross section, in some- 45 what the manner as illustrated by the line 10 in Figure 5 of the drawing.

I have also found that the drying takes place quite rapidly until it has dried to such an extent that this elliptical formation is 50 quite pronounced, after which the rapidity of the drying process decreases until the center has dried thoroughly. It often happens that on account of the length of time required to dry the center of the brick, they are placed 55 in the burning kiln before the center is completely dried, or while the center contains a

higher percentage of moisture than the outer surface, while as a matter of fact to obtain the best results in burning, the bricks should be uniformly dried before being placed in 60 the burning kiln. If the bricks are placed in the burning kiln before the centers and outer surfaces are of a uniform dryness, vapors and gases will be formed within the bricks, causing pressure strains as well as shrinkage 65 strains, which further assist in warping and cracking and internally straining the brick, and produces a product of very inferior quality and strength.

Referring to Figure 5, let it be assumed 70 that the drying has progressed to the elliptical line 10. It will then be seen that the distance from A to B is greater than the distance from C to D, and the distance from C to D is greater than the distance from E to F, 75 and that the outer drier surface is very ununiform in thickness, so that a number of weak points are established where cracks or fractures or strains may easily take place. It will further be seen that if the top and bottom 80 surfaces 11 and 12 of said brick were increased, the elliptical line 10 might be made to assume an elongated loop with its sides substantially parallel, as indicated by the numeral 13 in Figure 4.

To accomplish this result, I have formed in each of the outer side surfaces of the brick 85 a series of transversely and longitudinally extending V-shaped recesses 15, so that the said surfaces are provided with a series of 90 outwardly extending pyramids 16, thus increasing the exposed drying surface of the central portion of the side faces of the brick. The rapidity with which the brick dries is in proportion to the surface exposed to the 95 drying medium.

It will further be seen that the grooves 15 are deeper at their central portions than at their ends, so that the surfaces of the pyramids at their centers are considerably greater 100 than the surfaces of the pyramids at the edges and ends of the brick. The depth of these grooves can be so calculated that the drying line 10 shown in Figure 5 will assume a flatter condition, as illustrated by the line 13 in 105 Figure 4, thereby providing means whereby the sectional area of the drier portion of the brick is of substantially uniform thickness on all sides, and thereby eliminating to a large extent the possibility of weak points in 110 said drier portion, where cracking and warping and straining would take place.

To further illustrate this method of drying, let it be assumed that the distance from C to D in Figure 5 is equal to the distance from G to H in Figure 4. It will readily be seen that the time for drying the brick, as illustrated in Figure 5 from the point D to C, would be the same as required to dry the brick illustrated in Figure 4 from the point H to the point G. It will further be seen that the brick, as illustrated in Figure 4, is practically dried while the brick in Figure 5 is only about two-thirds dried.

In Figures 1, 2 and 3 I have shown the central portions of the sides of the brick formed with a series of pyramids which are deeper at the central portion of the brick. It will be seen that the same result might be accomplished by simply making either longitudinal or transverse grooves, some-
what as shown in Figure 6. I preferably leave a narrow band or border 17 around the outer edges of the side surfaces which has not been grooved, to form a protection for the pyramids 16, as well as to give the brick the appearance of being of rectangular formation, as viewed from the ends or edges.

It will further be seen that by providing the upper and lower surfaces of the brick with the pyramids 16, I have provided means whereby the shearing bond between the brick and the mortar joint will be greatly increased when the brick is laid in a wall construction. This is also a very desirable point, due to the fact that a mortar joint is the weakest point in the wall construction, especially in hard and vitrified brick, and bricks of this kind laid in mortar will make a wall of greater lateral strength than when not indented on the surfaces.

The diagrams in Figures 4 and 5 show the approximate condition that would take place if the plastic brick were subjected to a drying medium where all of its surfaces were entirely exposed thereto. It happens, however, in actual practice that the bricks are usually stacked on edge, while in the drying kiln, which considerably reduces the drying effect of the edges of the brick and would alter the shape of the elliptical line 10, causing it to be somewhat flatter than illustrated in Figure 5, in which case the depth of the central portions of the grooves 15 would have to be somewhat decreased. In fact, it will be seen that in actual practice other portions of the surface of the brick other than the center might have to be provided

with deeper grooves. The location of these deeper portions of the grooves would have to be arranged to meet the working conditions of the particular kiln and the manner in which they are set for the different processes in which the bricks are being dried, burned and cooled.

It is a well known fact that bricks are more or less under a continuous strain, due to expansion and contraction as they pass through the drying, burning, oxidizing and cooling stages. As they pass through the drying stage, the outer surfaces have a tendency to dry considerably faster than the central portions, as above described, causing rapid contraction of the drier portion of the material. When the bricks are placed in the burning stage, a reverse condition takes place, and the outer surface, being rapidly heated, expands in a reverse manner from the contraction, as above described, until it has reached the oxidation point, in which the carbonaceous fuels burn out of the brick and at the time vitrification takes place, shrinkage and contraction again takes place. As the bricks are rapidly cooled, it will be seen that the outer surface again contracts in about the same manner as described for drying.

Thus it will be seen that I have provided a brick so constructed that the contraction and expansion may be taken care of in such a manner that the time for drying, burning and cooling may be materially shortened without setting up disastrous internal and external strains.

I claim as my invention:

1. A brick of substantially rectangular formation, two of the opposite faces of said brick being provided with a series of intersecting grooves to form outwardly projecting members, the grooves being deeper at their central portions than at their ends, and so proportioned that the drying surface of said opposite faces will be gradually increased from their edges to their central portions.

2. A brick of substantially rectangular formation, two of the opposite faces of said brick being provided with grooves deeper at their central portions than their outer ends, so that the drying surface of said faces will gradually increase from their edges toward their central portions.

HALVER R. STRAIGHT.
